UNITED STATES PATENT OFFICE

MARY H. MULLEN, OF BRIGANTINE, NEW JERSEY

DESIGN FOR A BOTTLE

Application filed July 28, 1931. Serial No. 40,706. Term of patent 7 years.

To all whom it may concern:

Be it known that I, MARY H. MULLEN, a citizen of the United States of America, and resident of the city of Brigantine, county of Atlantic, and State of New Jersey, have invented a new, original, and ornamental Design for a Bottle, of which the following is a specification, reference being had to the accompanying drawing, forming a part thereof, in which—

Fig. 1 is a perspective view of the bottle.
Fig. 2 is a bottom plan view, on a smaller scale than Fig. 1.

Fig. 3 is a sectional view of the top portion of the bottle, on a smaller scale than Fig. 1.

I claim:

The ornamental design for a bottle, as shown.

MARY H. MULLEN.
